GUTTER PROTECTOR

Wyatt E. Abbitt, Charleston, W. Va.

Application June 19, 1934, Serial No. 731,336

1 Claim. (Cl. 108—30)

This invention relates to gutter protectors and has for its object the provision of a simple and efficient protector for gutters, eaves-troughs, and the like, whereby the gutter or eaves-trough may be kept free of leaves and other debris at all times, so that the water from the roof may pass off freely.

Another object of this invention is the production of a simple and efficient gutter protector which is so mounted upon the roof as to completely overhang the gutter and shield the same against the entrance of leaves and other debris, the protector being capable of being swung to an open position to permit access to the interior of the trough or gutter when desired.

A further object of this invention is the production of a simple and efficient gutter protector whereby the protector is made of a plurality of sections which are individually hinged to the roof so that the individual sections may be swung to an open position when desired.

A still further object of this invention is the provision of a simple and efficient gutter protector formed of wire mesh having transversely extending spaced reinforcing rods inserted therethrough for the purpose of stiffening and bracing the protector so as to prevent the protector from cupping or bending under the weight of snow and ice.

Another object of this invention is the provision of a simple and efficient hinge connection for hingedly securing the protector in engagement with a roof.

In the drawing:—

Figure 1 is a sectional perspective view through a portion of a roof showing one form of gutter construction commonly known as the secret gutter showing the improved protector in a closed position;

Figure 2 is a similar sectional perspective view to that as illustrated in Figure 1, the protector being shown in an open position;

Figure 3 is a top plan view of one of the sections of the protector showing the hinges secured thereto mounted upon a portion of the roof which is shown broken away for the purpose of illustration, the shingles being removed;

Figure 4 is a transverse sectional view through the protector and illustrating the hinge, taken on the line 4—4 of Figure 3;

Figure 5 is a plan view of the blank from which the hinge is constructed;

Figure 6 is a side elevation of the hinge illustrating the manner in which the hinge is bent to form its hinging connection with the protector

and illustrating the manner in which the cut-out spurs are bent to facilitate the anchoring of the hinge in position;

Figure 7 is a detail perspective view illustrating the manner in which the hinge is connected to the protector and also showing in enlarged detail one of the stiffening rods.

By referring to the drawing, it will be seen that 10 designates the building upon which the gutter structure 11 is built, the building carrying a 10 suitably inclined roof 12 which is preferably covered with shingles 13 of any suitable or desired type. The gutter 11 illustrated is of the secret gutter type, but it should be understood that any 15 suitable or desired form of gutter may be employed without departing from the spirit of the invention. In order to close the top of the gutter and thereby shield the gutter against the entrance leaves and other debris which would tend to clog up or to deteriorate the gutter, I provide 20 a protector 14 which comprises a plurality of 20 individually hinged sections 15, and these sections 15 are preferably made approximately three 25 feet in length and are a sufficient width to span the distance from the edge of the roof to the forward edge of the trough 11. Each section 15 25 comprises preferably a rectangular wire mesh screen body preferably one-half inch square mesh, or hardware mesh, being galvanized or copper. Located near each end and extending transversely across the body of each wire mesh section 15 is an end stiffening wire 16 preferably 30 #14 gauge and of larger gauge than the wire mesh body, as shown in Figures 1, 2 and 3, the wire 16 being alternately threaded through the 30 mesh, such for example as illustrated in Figure 7, although it should be understood that this stiffening wire may be in any manner secured without departing from the spirit of the invention. Intermediate transversely extending stiffening 35 wires 17 also of larger gauge than the wire mesh body as shown in Figures 1, 2, and 3, are also secured and carried by the wire mesh body or section 15, and are preferably arranged at equally spaced intervals to efficiently reinforce the wire mesh section 15 and brace the section so as to prevent the same from cupping or bending under the weight of the snow or ice. I employ 40 a plurality of these sections 15 which are arranged to have their adjacent ends in relatively close abutting relation, such as is shown in Figures 1 and 2 to provide a continuous shield 45 throughout the entire length of the gutter or eaves-trough. Any suitable or desired number 50 may be employed and by providing the protector 55

in a plurality of sections, the sections may be raised and lowered without difficulty to obtain access to the interior of the gutter, and at the same time will not have a tendency to warp or 5 get out of shape as would be the case if relatively long sections were provided or if the protector were made in one piece.

The sections 15 are preferably hingedly connected to the roof at four approximately equally 10 spaced points by means of especially constructed hinge or clip members 18. Each hinge member is preferably formed from a blank sheet of material of any suitable metal or other similar material, as is shown in detail in Figure 5. Each 15 hinge member is provided with a projecting tongue 19 which is rolled, as indicated in Figure 6, to provide a journal and to extend over one of the longitudinally extending wires, preferably the wire 20 extending along the rear edge of the 20 section 15 thereby permitting the sections to be easily and conveniently swung. The body of the hinge is provided with a plurality of angular slits 21 along one side edge and a plurality of angularly extending slits 22 upon the opposite 25 side edge as shown in Figure 5, to permit of the formation of oppositely extending pointed spurs 23 and 24 upon opposite sides of the body of the hinge members 18. These spurs 23 and 24 will 30 constitute an efficient means for holding the hinge members 18 in position without the necessity of employing additional securing means. When mounting the parts in position the clips or hinge members 18 are forced under the roofing or shingles 13, the spurs 24 biting into the 35 roof 12 and the spurs 23 biting into the underface of the roofing or shingles 13. The hinge mem-

bers or clips 18 will, in this manner, be held firmly in position. The projecting tongue 19 is then threaded through the wire mesh section 15 so as to extend around the rear strand of the wire as shown in Figure 7, to provide an efficient hinge 5 connection. The forward edges of the sections 15 will then rest upon the forward edge of the gutter 11, and by lying substantially flat upon the forward edge of the gutter, the protector screen will be shielded from view from the outside. 10

It should be understood that certain detail changes in the mechanical construction, combination and arrangement of parts may be employed without departing from the spirit of the invention, so long as such changes fall within the 15 scope of the appended claim.

Having described the invention, what is claimed as new is:

As a new article of manufacture, a gutter protector comprising an elongated wire mesh body, 20 transversely extending reinforcing stiffening wires of a larger gauge than the wire mesh body arranged in spaced relation throughout the length of the body intermediate the ends of the body and extending across the full width of the 25 body from the rear edge to the front edge thereof whereby the body throughout its length may be stiffened and braced at spaced intervals to prevent the sagging and warping of the wire mesh body when leaves and other debris accumulate 30 upon the body, the wire mesh body constituting the sole marginal outer edge of the protector, and hinge means secured to the body in close proximity to the stiffening wires. 35
